Louis P. Zelenka, Mount Lebanon, Pa., assignor to Commonwealth Sanitation Company, Pittsburgh, Pa., a corporation of Pennsylvania

Application June 12, 1953, Serial No. 25,463

Term of patent 14 years

(Cl. D16—2)

To all whom it may concern:

Be it known that I, Louis P. Zelenka, a citizen of the United States, residing at Mount Lebanon, Pittsburgh, State of Pennsylvania, have invented a new, original, and ornamental Design for Deodorizer, of which the following is a specification, reference being had to the accompanying drawing, forming a part hereof.

The figure is a perspective view of a deodorizer, embodying my new design. The other side is like the side shown and the bottom is flat and plain.

I claim:

The ornamental design for a deodorizer, as shown and described.

LOUIS P. ZELENKA.
